(57) **CLAIM**

The ornamental design for a horizontal ornamental hand sign with "_____s on T.V.", as shown and described.

DESCRIPTION

FIG. 1 is a perspective view of one embodiment of a horizontal ornamental hand sign with "_____s on T.V." demonstrating its basic form.

FIG. 2 is a frontal view of the embodiment depicted in FIG. 1.

FIG. 3 is a bottom view of the embodiment depicted in FIG. 1.

FIG. 4 is a rear view of the embodiment depicted in FIG. 1.

FIG. 5 is a top view of the embodiment depicted in FIG. 1.

FIG. 6 is a side view of the embodiment depicted in FIG. 1, taken from the right side; and,

FIG. 7 is a side view of the embodiment depicted in FIG. 1, taken from the left side.

The indicia in broken lines are for illustrative purposes only and form no part of the claimed design.
